PROCESS OF TREATING COAL

Filed Jan. 29, 1930

UNITED STATES PATENT OFFICE

CHARLES P. ANDERSON, OF SCARBRO, WEST VIRGINIA

PROCESS OF TREATING COAL

Application filed January 29, 1930. Serial No. 424,314.

This invention relates to a process of treating coal and is particularly adapted to treating bituminous and anthracite coals.

- An object of the invention is to provide a process that in a continuous operation will separate the impurities from the run of mine coal and all sizes of screened coal and at the same time provide for rendering the coal dustless after the treatment.
- 10 Further objects of the invention are to provide a process, the outcome of which causes more complete combustion of the coal and reduces the amount of smoke.

With the foregoing and other objects in view, the invention consists of a novel treating operation that will be more particularly described and illustrated in the accompanying specification, wherein is disclosed an embodiment of the invention, but it is to be understood that changes, variations and modifications may be resorted to without departing from the spirit of the claims hereto appended.

The figure in the drawing, represents a diagrammatic treating operation in accordance with the present invention.

It has been proposed to separate impurities from coal by the use of calcium or zinc chloride solution of a specific gravity to effect the flotation of the coal but as far as the applicant has been able to determine the coal is washed after treatment to remove the calcium or zinc chloride.

It has also been proposed to apply calcium or calcium and magnesium chloride to coals after screening to prevent dust from coming from the coal. In this latter aspect the solution is merely applied to the surface of the coal which precludes the possibility of gaining anything but a superficial coating on the surface of the coal.

It therefore is an object of the invention to immerse the bituminous and anthracite coal in an aqueous solution formed of salts or mixtures of salts of certain metals, such as those of certain alkaline earth metals, the specific gravity of which has been built up to cause the coal to float on the surface and the impurities to settle to the bottom of the container used in the treatment.

In a continuous operation the coal of my invention, is then taken from the solution without any washing or other treatment and stored in bins for future use or loading in railroad cars or passing over screens to be loaded in trucks or railroad cars, and with this practice in mind it will be found that the solution, by capillary attraction, will adhere to or penetrate beneath the surface of the coal and this adhesion and penetration will not only render the coal dustless but will create a more perfect combustion, thereby retarding the smoke and at the same time increasing the B. t. u. value of the coal.

The average practically available heat content of coals coming from a particular field in West Virginia, where experiments have been made, average about 14,800 B. t. u. per ton, whereas an average value, after treatment in accordance with the present invention will result in a coal having approximately 15,250 B. t. u.

Moreover, an analysis of the coal after treatment, shows a considerable reduction in ash from which it is to be presumed that there is a more perfect combustion and a noticeable decrease in the amount of smoke.

In explaining the process of the treating of the coal and referring to the drawings in detail, 1 represents a chute from which screened run of mine coal is to be treated. By this latter term is meant coal as it comes from the mine containing clay, slate, dirt, and other refuse. Coal passes from the chute into a reservoir 2 that may be supported on any elevated superstructure 3.

The average specific gravity of coal of bituminous character ranges from 1.28 to 1.46 and coal of anthracite character ranges from 1.40 to 1.65 and therefore the aqueous solution 4 in the tank is built up so that the specific gravity will cause the pure coal indicated at 5 to float along the surface of the solution.

The refuse, slate or other impurities being of a heavier specific gravity and indicated at 6, will precipitate or sink to the bottom of the reservoir 2. A frame 7 may be suitably supported as at 8 on the reservoir 2 about which is movably trained an endless conveyor 9 having

foraminous buckets 10 connected therewith. This conveyor may be arranged in any suitable manner with respect to the reservoir, so as to engage the floating coal 5 and carry the same out of the reservoir.

10 The coal passes then from the endless conveyor 9 onto another endless conveyor 11 which is associated in proximity to the end of the conveyor 9, whereupon the coal from this latter conveyor 11 will fall in the storage pile 12.

15 The apparatus for carrying out the invention may be altered as the circumstances require having in mind the most efficient operation for a continuous process. It will be seen from the foregoing description, that the treatment of the coal is continuous and requires the minimum of attention during its operation.

20 It is preferred to have the lower end of chute 1 below the level of the treating liquid 4 so as to insure complete immersion of the coal in the liquid. Furthermore, it will be noticed that it is preferred to have the lower end of the inlet conveyor 9 spaced from the chute so as to provide suitable space therebetween for the coal to float on the surface and allow the maximum time for capillary attraction of the salt solution beneath the surface of the coal.

25 30 In forming the solution for treating in reservoir 2, an aqueous solution of the salts of certain metals such as magnesium, calcium or other chlorides, for example, zinc chloride, is built up to the specific gravity required in a separate reservoir from the treating reservoir 2 and conveyed into reservoir 2 in any suitable manner.

35 40 In this way, a constant specific gravity of the treating solution is obtained. Obviously, the present invention does not contemplate any further treatment of the coal after immersion in the metal salt treating solution, thereby eliminating expensive washings that are frequently used on the market today, and 45 moreover it will be noted that in making an application of the salt to the coal, use of the salt solution, permits the separation of the impurities from the coal, which entirely eliminates expensive separations, heretofore proposed before applying superficial coatings to prevent dust.

50 55 It therefore follows that the present invention contemplates a continuous operation for separating impurities from coal and rendering the coal dustless, and dustproof, promoting better combustion with a corresponding reduction in smoke and slightly increasing the B. t. u. value of the coal.

60 65 It is to be understood by describing in detail herein any particular form, arrangement, or sequence of operation, it is not intended to limit the invention beyond the terms of the several claims, or the requirements of the prior art.

Having thus described my invention, what I claim as new is:—

1. A method of treating coal comprising immersing screened run of mine coal in an aqueous solution containing a salt of an alkali metal of a specific gravity to cause the pure coal to float, and permit the heavier impurities to sink, permitting the floating coal to remain in the solution until it has mechanically entrained the maximum amount of the solution and thereafter continuously conveying the coal from the receptacle and causing the coal to permanently retain all of the adsorbed salt. 70 75

2. A method of treating coal comprising immersing screened run of mine coal in an aqueous solution containing a mixture of a metal salt of a specific gravity to cause the pure coal to float, and permit the heavier impurities to sink, permitting the floating coal to remain in the solution until it has mechanically entrained the maximum amount of the solution and thereafter conveying the coal from the receptacle to a place of storage or deposit of the finished product, and causing the coal permanently to retain all of the salt entrained thereby in said receptacle. 80 85 90

3. A method of treating coal comprising the single step of separating impurities from the coal in the presence of a solution of salt of an alkaline earth metal, and removing the separated coal as a finished product permanently retaining the adsorbed salt solution. 95

4. A method of treating coal comprising the single step of separating impurities from coal in the presence of a mixture of salt of an alkaline earth metal, and removing the separated coal as a finished product permanently retaining all of the entrained salt mixture. 100

105 In testimony whereof I affix my signature. CHARLES P. ANDERSON.
